FOR PLUMBING FIXTURES OR THE LIKE

Henry Dreyfuss, South Pasadena, Calif., assignor to Crane
Co., Chicago, Ill., a corporation of Illinois

Application August 8, 1958, Serial No. 52,134

Term of patent 14 years

(Cl. D91—3)

Fig. 1 is a perspective view of a lever actuator and dial combination for plumbing fixture or the like embodying my new design;

Fig. 2 is a top plan view thereof; and

Fig. 3 is a side elevational view thereof.

The dominant features of my design reside in the portions shown in full lines.

I claim:

The ornamental design for a lever actuator and dial combination for plumbing fixtures or the like, substantially as shown and described.
